LIQUID LEVEL CONTROL

Application filed July 27, 1928. Serial No. 295,674.

This invention relates to an apparatus for controlling the level of liquid accumulating in a container and is particularly adapted to the control of liquid accumulating in a container where the liquid is at its boiling point and of such a character that the ordinary control devices do not function properly if placed therein. My invention is particularly adapted to the control of the liquid 10 level of petroleum hydrocarbons, such as the complex mixtures produced by cracking and which are in equilibrium with a vapor phase, as for example in a separator, still or rectifying column. In accordance with my 15 invention a minor part of the vapor phase is continuously condensed and diverted into a receptacle, the liquid level in which receptacle is in hydrostatic equilibrium with the liquid level in the main container so that the level 20 control devices are surrounded by and actuated by the condensate so produced and not by the residua which have accumulated in the principal container. In the case of petroleum hydrocarbons these residua are particularly apt to form coky deposits which seriously interfere with the operation of any level control device placed therein, and this difficulty is entirely eliminated by my 25 invention.

30 The invention will be understood from the following description read in conjunction with the drawing; in which

Fig. 1 is an elevation with parts in section of a preferred embodiment of my invention;

35 Fig. 2 is a top view of a part of Fig. 1 showing an auxiliary form of pumping apparatus;

Fig. 3 is a vertical section through a form 40 of valve control apparatus shown in Fig. 1;

Fig. 4 is a horizontal section through part 45 of Fig. 1 on the plane denoted by the line 1-1; and

Fig. 5 is an outside view of a part of Fig. 1. Referring to Fig. 1, the numeral 1 denotes 50 a container in which a liquid is fractionated, such as a separator or rectifying column. This rectifying column has an inlet pipe 2 from which material such as a mixture of petroleum hydrocarbons partly in the vapor 55 phase may be supplied to the column. The column is equipped with a series of horizontal partitions 3 which, in turn, carry liquid vapor contacting devices, such as bell caps and overflow pipes, not shown. A cooling coil 4 is preferably provided in the upper part of the column, and the vapor outlet pipe 5 is adapted to carry the finally rectified vapors away from the column. Any liquid bottoms 60 accumulating in the base of the column may be withdrawn through the pipe 6 which is connected to the suction side of the oil pump 7. The pumped oil may be discharged through the pipe 8 leading from the discharge side of the pump to an accumulator. A side 65 inlet 9 is tapped off from the column at a point above the liquid level and preferably adjacent the upper part of the column 1. This pipe may be left uncovered to provide a certain amount of condensation but is preferably surrounded in part by a condenser, such as 10, equipped to receive cooling liquid by means of the inlet and outlet pipes 11 and 12, respectively. The pipe 9 discharges into a receptacle 13 which is positioned so as to include the upper and lower limits, respectively, of the level to be controlled in the column 1. The receptacle 13 is connected back into the column at a point below the liquid level by the pipe 14, so that the levels within the receptacle 13 and column 1 will always be in substantial hydrostatic equilibrium. A float 15 is provided in the receptacle 13 Fig. 4 which is rigidly connected to the shaft 16 which, in turn, extends through the stuffing box 17 on the side of the receptacle 13. This shaft is connected directly to the plug 19 in the cock 18, so that the upward movement of the float will operate to open the cock 18 and the converse downward movement of the float will operate to close it. 18 is located in the pipe 20 and is therefore adapted to throttle and control the flow of liquid through the said pipe. The receptacle 21 in the said pipe provides a reservoir of liquid, the level of which may be observed by means of the sight gauge 22. The pipe 20 is connected to the suction side of a small auxiliary pump 23 which is bolted to, or otherwise rigidly secured to, the steam end 24 of the pump 7. This pump is of 100

the conventional piston type operated by the shaft 25 which enters the pump through the stuffing box 26. The piston rod carries the yoke 27 Fig. 2, which, in turn, is actuated by the carrier 28 which is ordinarily a rod attached to the pump 7 and projecting upwardly so as to carry the yoke 27 through a part of its travel and thereby cause the pump 23 to force a small quantity of liquid, having a direct proportionality to the amount of liquid going through the main pump 7. The pump 23 is provided with conventional inlet and outlet valves, not shown, so that the discharge from the pump passes away through the pipe 15 into a piston chamber 31. This piston chamber Fig. 3, carries a weighted piston 32 connected to a piston rod 33 which at its upper extremity carries a pin 34. This pin engages a slot 35 in the weighted handle of the cock 36 which controls the flow in the pipe 37 carrying steam to the steam end of the pump 7. A cover plate 38 is provided on the piston chamber so that the piston 32 will never be completely expelled from the piston chamber 31. The pipe 20 leads from the piston chamber 31 back to the cock 18, thereby permitting a continuous circulation of the pumped liquid from the reservoir 21 through the pump 23, piston chamber 31 and back to the reservoir 21 subject to the throttle control of the float 15 operating through the cock 18.

In operation material to be rectified, such as cracked material withdrawn from the digesting column of a cracking unit operating on petroleum oil, is introduced to the column 1 through the pipe 2. Cooling medium is supplied through the coil 4 to control the degree of rectification taking place in the rectifying column and thereby produce a desired composition of overhead vapor which is diverted away through the pipe 5. Bottoms, or heavy residuum, accumulates in the base of the column 1, while liquid and vapor phases in partial equilibrium exist above the several horizontal partitions 3 becoming progressively lighter and lower in boiling point as the top of the column is approached. Part of the material in the upper part of the column, preferably the vapor, is diverted continuously through the pipe 9 and, if not already liquid, is condensed in the condenser 10 and flows downwardly into the receptacle 13, thereby maintaining in the receptacle 13 a level of liquid substantially identical with the level existing in the column 1. It will be noted, however, that the composition of the liquid in the receptacle 13 is that of the material adjacent the upper part of the column 1, which in practice will be fluid relatively stable and not of such a character as would form carbonaceous deposits and gum up or stop a control mechanism, whereas on the contrary the liquid residua accumulating in the base of the column may be of an asphaltic or tarry character and may have a

strong tendency to form a deposit which would seriously interfere with the operation of any liquid level device in position in the column.

As the level in the column rises, the float 15 floats upwardly proportional thereto and operates to open the cock 18, thereby releasing the pressure in the piston chamber 31. This automatically permits the piston 32, the piston rod 33 and pin 34 to fall, thereby operating to open the cock 36 in the steam line 37 and either starting the pump 7 or causing it to operate more rapidly. The operation of the pump 7 carries in operation the pump 23, thereby pumping a continuous supply of liquid from the reservoir 21. Whenever the liquid level in the column 1 has fallen to a predetermined point the float 15 will operate conversely to close the cock 18, thereby causing an accumulation of pressure in the piston chamber 31 which operates conversely to close, or partly close, the valve 36 thereby cutting down the steam and slowing down the pump until the predetermined level in the column is again attained. In practice very little hunting is observed. The adjustment of the pump speed by my device will ordinarily be such that very little variation in liquid level in the column is experienced, and the column operates continuously at substantially the predetermined and desired liquid level therein.

It will be apparent from the foregoing that my liquid level control device is free from the difficulties which have characterized previous control devices positioned within the column itself and is susceptible of continuous and efficient operation regardless of the refractory character of the liquid bottoms in the main container, the level of which is to be controlled.

It will of course be understood that the foregoing specific description of apparatus is by way of illustration and not of limitation. It is my intention that the invention be limited only by the appended claims, or their equivalents, in which I have endeavored to claim broadly all inherent novelty.

I claim:

1. A device for controlling the level of liquid accumulating in a container comprising a receptacle positioned substantially at the level of the liquid to be controlled, a connection between said receptacle and said container below the liquid level to be controlled, a primary pump connected to said container below the level to be controlled, an auxiliary pump actuated by said primary pump, means for supplying liquid to said auxiliary pump, a discharge circuit from said auxiliary pump, means responsive to variations in level in said receptacle adapted to regulate the discharge from said auxiliary pump and thereby vary the pressure in said discharge circuit, and means for controlling the primary pump re-

sponsive to variations in pressure in said discharge circuit.

2. A device for controlling the level of liquid accumulating in a container comprising a liquid discharge outlet from said container, a primary pump connected to said discharge outlet, a receptacle positioned at substantially the level to be controlled, a pipe connecting said receptacle with said container below the level to be controlled, means for abstracting material from the said container at a point above the level to be controlled, and for discharging said material in liquid form into the said receptacle, means responsive to the liquid level in said receptacle, an auxiliary pump actuated by said primary pump, means for supplying liquid to said auxiliary pump, a discharge circuit from said auxiliary pump, means for causing the said means responsive to variations in liquid level to regulate the discharge from said pump and thereby vary the pressure in the said discharge circuit, and means controlling the said primary pump responsive to variations in pressure in said discharge circuit.

3. A device for controlling the level of liquid accumulating in a container comprising a discharge outlet from said container, a primary pump connected to said discharge outlet, a receptacle positioned at substantially the level to be controlled, a pipe connecting said receptacle with said container below the level to be controlled, means for abstracting material from the said container at a point above the level to be controlled and for discharging the material abstracted in liquid form into the said receptacle, a float in said receptacle, an auxiliary pump actuated by said primary pump, means for supplying liquid to said auxiliary pump, a discharge circuit leading from said auxiliary pump connected to said receptacle, a flow control device, means for causing movement of said float to vary the adjustment of a flow control device whereby variations in level in said receptacle operate to regulate the discharge from said discharge circuit outlet and thereby vary the pressure in said discharge circuit, means for controlling the said primary pump responsive to variations in pressure in said discharge circuit.

4. In combination with a column for fractionating a liquid having relatively high and low boiling components, a device for controlling the level of a relatively high boiling liquid accumulating in said column comprising a receptacle, a pipe connecting the receptacle with said column at a point below the level to be controlled, means for causing relatively low boiling material withdrawn from the upper part of said column to be discharged into the said receptacle in liquid form, whereby circulation is established and said receptacle will in operation contain substantially exclusively relatively low boiling

material withdrawn from the upper part of said column, and means responsive to the liquid level in said receptacle for controlling the liquid level in said column.

5. In combination with a column for fractionating a liquid having relatively high and low boiling components, a device for controlling the level of a relatively high boiling liquid accumulating in said column comprising a receptacle, a pipe connecting said receptacle with said column at a point below the level of the relatively high boiling components to be controlled, a pipe connecting the receptacle with said column at a point above the level to be controlled, a condenser connected to the last-mentioned pipe whereby relatively low boiling products condensed in said condenser are discharged into said receptacle, a float in said receptacle, and means responsive to movement of said float for controlling the liquid level in said column.

6. In a fractionating system in combination, a fractionating column, means for introducing a fluid mixture to said column, said fluid mixture having both high and low boiling components, means for withdrawing overhead fractions from said column, means for withdrawing liquid residue from the bottom of said column comprising a discharge pipe and a primary pump connecting therewith, and means for controlling the liquid residue level in said column comprising a receptacle positioned adjacent the lower section of said column, a pipe connecting said receptacle with said column at a point below the liquid level therein, means for withdrawing fluid from said column at a point above the liquid level therein and for discharging said fluid to said receptacle in liquid condition whereby the liquid in said receptacle comprises only low boiling components of the original fluid mixture introduced into said column, an auxiliary fluid circulating system communicating with both said receptacle and with said primary pump, means for introducing fluid into said circulating system, means for causing circulation of said fluid in said circulating system, means responsive to the variations in the liquid level in said receptacle for causing pressure variations in said circulating system, and means responsive to said pressure variations for regulating said primary pump.

7. In a fractionating system in combination, a fractionating column, means for introducing a fluid mixture to said column, said fluid mixture having both high and low boiling point components, means for withdrawing overhead fractions from said column, means for withdrawing liquid residue from the bottom of said column comprising a discharge pipe and a primary pump connecting therewith, and means for maintaining said liquid residue in said column at a desired level comprising a receptacle positioned sub-

stantially at the liquid residue level to be maintained, a pipe connecting said receptacle with said column at a point below the liquid level therein, means for withdrawing fluid from said column at a point above the said desired liquid residue level and for discharging said withdrawn fluid to said receptacle in liquid condition, an auxiliary fluid circulating system, means for introducing fluid thereto,
16 an auxiliary pump in said circulating system actuated by said primary pump and operating to cause the circulation of the fluid in said circulating system, means communicating with said circulating system and responsive to variations in the liquid level in said receptacle for causing pressure variations in said circulating system, and means communicating with said primary pump and responsive to said pressure variations for controlling the operation of said primary pump whereby the desired liquid residue level is maintained in said column.

In testimony whereof, I have signed my name to this specification this 24th day of
25 July, 1928.
